J. H. HAMMOND, JR.
 SYSTEM OF TELEDYNAMIC CONTROL.
 APPLICATION FILED APR. 8, 1913. RENEWED SEPT. 22, 1916.
 1,418,794.

Patented June 6, 1922.

UNITED STATES PATENT OFFICE.

JOHN HAYS HAMMOND, JR., OF GLOUCESTER, MASSACHUSETTS.

SYSTEM OF TELEDYNAMIC CONTROL.

1,418,794.

Specification of Letters Patent. Patented June 6, 1922.

Application filed April 8, 1913, Serial No. 759,612. Renewed September 22, 1916. Serial No. 121,689.

To all whom it may concern:

Be it known that I, JOHN HAYS HAMMOND, Jr., a citizen of the United States, residing at Gloucester, in the State of Massachusetts, have invented certain new and useful Improvements in Systems of Teledynamic Control, of which the following is a specification.

My invention relates to systems for controlling and operating mechanisms and apparatus at a distance, and relates more particularly to a system of multiple control, in which two or more torpedoes or other craft can be controlled and operated simultaneously from a distant station, or in which apparatus on a master vessel can be operated from a distant station, and can in turn control and operate apparatus and mechanisms on one or more auxiliary vessels.

In the accompanying drawings:—

Fig. 1 shows, in diagrammatic form, an application of my system, in which three torpedoes, or similar vessels, are controlled and operated simultaneously, it being understood that there is a transmitting station capable of sending out tuned electrical oscillations to be received by the receiving station on one of the vessels.

Fig. 2 shows an end view of a cable reel and spring, forming a detail of my system.

Fig. 3 shows a side view of this cable reel.

In Fig. 1, X is a submarine or submersible vessel containing a receiving station for radiant energy. X¹ is a torpedo or other submarine vessel connected with X by a cable W containing an insulated conductor, and X² is another torpedo or other vessel connected with X¹ by a cable W¹. X may be called the master vessel and X¹ and X² auxiliary vessels. A is a receiving antenna, in circuit with the inductance coil L and variable condenser C and grounded at E. The oscillation circuit L¹ C¹, comprising the inductance coil L¹ and variable condenser C¹, is coupled to the antenna circuit by means of the coils L and L¹, and both this oscillation circuit and the antenna circuit are tuned to the wave length of the corresponding transmitting station. By means of the stopping condenser D and the rectifier R, unidirectional current impulses are supplied to the relay F, which, when actuated, allows current to flow from battery B through circuits 1 and 2 to the electromagnet G. K is a rotatable cylindrical commutator, operated by the electromagnet G in the manner described

in various other applications of mine for United States Letters Patent, such as Serial Nos. 750,983 and 755,841. On the commutator K are contact pieces, in pairs, with neutral spaces between them, and these contact pieces make contact with brushes which are connected with the circuits 5, 6 and 7. Circuit 5 connects with electromagnet M, circuit 7 with electromagnet M¹, and circuit 6 is a return circuit from both these electromagnets containing the battery B¹. The contacts on the commutator K are so arranged that electromagnets M and M¹ are energized alternately, and never at the same time, and so that there is a neutral position of the commutator when neither electromagnet is energized.

Electromagnets M and M¹ control the operation of valves U and U¹, respectively, and these valves regulate the admission of compressed air, or other suitable fluid, from the tank T into the cylinder O. According as to which valve is operated, the piston P in cylinder O moves to the right or to the left, and being attached by means of the piston rod Q to the helm S, the latter is moved to starboard or to port, and so turns the rudder Y to port or to starboard. The springs Z and Z¹ tend to keep the helm and the rudder in a central position amidships and bring them back to this central position when the valves cease to operate.

The details of the above described mechanisms are more fully shown and described in my application for United States Letters Patent, Serial No. 750,983, above cited, and I may employ other forms of mechanisms, suitable for my purposes such for instance, as shown in my application, Serial No. 755,841.

A branch circuit 3 runs from the relay F to the brush J, which bears against a circular conducting strip on the cable reel H, on which is wound a portion of the cable W, the end of the conductor in cable W being in electrical contact with the strip against which the brush J bears. The cable W runs to the torpedo X¹ and is there connected with a battery B², which is connected with the relay F¹. Circuit 4, connecting relay F with ground E¹, and circuit 8, connecting relay F¹ with ground E², complete the circuit between relays F and F¹, so that whenever relay F is actuated, relay F¹ on torpedo X¹ is actuated at the same time. Batteries B and B² are made equal and connected so that

their electromotive forces will oppose each other, and thus prevent any flow of current through electromagnet G and relay F¹ unless relay F¹ is actuated.

5 Relay F¹, when actuated, allows current to pass from battery B³ through the electromagnet G¹. K¹ is a rotatable cylindrical commutator, operated by the electromagnet G¹. On the commutator K¹ are contact 10 pieces, in pairs, with neutral spaces between them, and these contact pieces make contact with brushes which are connected with the circuits 9, 10 and 11. Circuit 9 connects with electromagnet M², circuit 11 with electromagnet M³, and circuit 10 is a return circuit from both these electromagnets containing 15 the battery B⁴.

Electromagnets M² and M³ control the operation of valves U² and U³, respectively, 20 and these valves regulate the admission of compressed air, or other suitable fluid, from the tank T¹ into the cylinder O¹. According as to which valve is operated, the piston P¹ in cylinder O¹ moves to the right or to the 25 left, and being attached by means of the piston rod Q¹ to the helm S¹, the latter is moved to starboard or to port, and so turns the rudder Y¹ to port or to starboard. The springs Z² and Z³ tend to keep the helm and 30 the rudder in a central position amidships. x¹ is a compartment containing explosives.

The details of the above described mechanisms are more fully shown and described in other applications of mine for United 35 States Letters Patent, such as Serial No. 750,983, above cited, and these mechanisms and apparatus on torpedo X¹ operate at the same time as, and in a similar manner to the corresponding mechanisms and apparatus on vessel X, so that both craft move 40 at the same time and in the same direction.

A branch circuit runs from relay F¹ to a brush J¹ which bears against a circular conducting strip on the cable reel H¹ on which 45 is wound a portion of the cable W¹, the end of the conductor in cable W¹ being in electrical contact with the strip against which the brush J¹ bears. The cable W¹ runs to the torpedo, or other vessel, X² and is there 50 connected with a battery B⁵ which is connected with the relay F². Ground E³, connected with relay F¹, and ground E⁴, connected with relay F², complete the circuit through relays F¹ and F² and cable W¹, so 55 that whenever relay F¹ is actuated, relay F² is actuated at the same time. Batteries B³ and B⁵ are made equal and connected so that their electromotive forces will oppose each other, and thus prevent any flow of 60 current through electromagnet G¹ and relay F² unless relay F¹ is actuated. Connected with relay F² on vessel X² are apparatus and mechanisms similar to those on vessel X¹, which need not be more particularly described here, so that the movements of ves-

sel X² correspond with those of vessel X¹. A compartment x² contains explosives.

In Figures 2 and 3, H is a cable reel on which a portion of cable W is wound, I is a spring tending to wind up the cable W on the reel, and J is a brush connecting with circuit 3 and making contact with a circular strip j, with which the end w of the conductor in cable W is also in electrical contact. Cable reel H¹, on vessel X¹, is similar to cable reel H, and has a similar spring, and brush J¹ on vessel X¹, is similar to brush J. These cable reels and springs are for the purpose of securing more flexibility in the cable connections between the vessels and they will minimize any shocks and strains on the cables and connections. 80

The cables W and W¹ may contain complete metallic circuits between the vessels, in which case the grounds E¹, E², E³ and E⁴ 85 would be omitted. In some cases the relays F¹ and F² can be omitted, and the mechanisms on the vessels X¹ and X² can be operated directly through branch circuits (carried by the cables W and W¹) from relay F. 90 Vessel X² might be placed on the side of vessel X opposite from vessel X¹ and might be operated through a cable direct from vessel X, either in this new position or in any other position. 95

I do not confine myself to the operation of three vessels, but I may operate any convenient number simultaneously by running cables from the master vessel to each auxiliary vessel, or by running cables from the master vessel to the first auxiliary vessel, then from the first auxiliary vessel to the second auxiliary vessel, and so on. If these vessels are designed to operate against an enemy, I may carry explosives on them all, but preferably I should carry explosives only on my auxiliary vessels, for the master vessel, being the only one with masts, would offer a target for the enemy, while the auxiliary vessels, being entirely under water, their position and even their presence would be entirely unknown to the enemy, against whom they would therefore be all the more effective. The master vessel can also have its vital parts protected 100 against rapid fire guns or machine guns by means of armor plate. 110

Instead of having my master vessel controlled from a distance, I can use a submarine or submersible vessel with one or 120 more persons on board, and controlled by them, and my auxiliary vessels can be sent ahead of my master vessel, or in any other desired direction, and can be controlled by the crew of my master vessel. 125

Other forms of mechanism may be used for steering the three vessels X, X¹ and X², such as I find suitable for my purposes, and other apparatus for controlling and operating the vessels, in addition to steering them, 130

may be operated simultaneously on the three vessels by my system; and, in general I do not confine myself to the particular apparatus and mechanisms here shown, but various changes and modifications, within the knowledge of those skilled in the art, may be made in the particular apparatus shown and described herein, without departing from the spirit of my invention, provided the means set forth in the following claims be employed.

Having thus described my invention, I claim:—

1. In a system of multiple control for vessels, a primary vessel controlled by radiant energy, a plurality of secondary vessels controlled through electric cables by said primary vessel, and automatic means for operating said secondary vessels from said primary vessel.

2. In a system of teledynamic control, a tuned radio transmission station, a vessel containing tuned radio receiving apparatus and controlled from said station, a plurality of auxiliary vessels connected with said first mentioned vessel by electric cable and controlled from said first-mentioned vessel, and means for producing corresponding operations simultaneously in all of said vessels.

3. A system of multiple control for vessels, comprising a transmitting station for radiant energy, a submarine vessel containing a receiving station for radiant energy and apparatus operatively connected with said receiving station for operating said vessel, a plurality of torpedoes electrically connected with said submarine vessel, and apparatus on each of said torpedoes for operating it, said apparatus being automatically controlled from the submarine vessel.

4. In a system of multiple control for vessels, a submarine vessel controlled from a distance, a plurality of torpedoes connected by electric conductors with said submarine vessel, and automatic means for controlling said torpedoes from said submarine vessel.

5. A system of distance control for vessels comprising a transmitting station for radiant energy, a vessel containing a receiving station for radiant energy and apparatus for steering said vessel, and a plurality of other vessels connected with said first vessel, each vessel comprising separate steering apparatus, said apparatus being automatically controlled from said first vessel.

6. In a system of multiple control for vessels, a vessel controlled from a distant station, a plurality of auxiliary vessels connected successively by electric cable with said first-mentioned vessel, and means for controlling operating mechanisms on said auxiliary vessels successively.

7. In a system of multiple control for vessels, a master vessel, a second vessel connected by means of an electric conductor

with said master vessel, electric means for controlling said second vessel from said master vessel, a third vessel connected by means of an electric conductor with said second vessel, and electric means for controlling said third vessel from said second vessel.

8. In a system of multiple control for vessels, a master vessel, a plurality of auxiliary vessels at different distances from the master vessel and successively connected therewith by electric cable, means for controlling one of the auxiliary vessels direct from the master vessel, and means for controlling the other auxiliary vessels from each other successively, substantially as described.

9. The combination with a movable body, of means carried thereby and responsive to radiant energy for controlling the direction of movement of said body, a body movable independently of said first mentioned body, and means carried by said second mentioned body and controlled by said first mentioned means for controlling the direction of movement thereof.

10. The combination with a movable body, of means carried thereby and responsive to radiant energy for controlling the direction of movement of said body, a body movable independently of said first mentioned body, and functioning means carried by said second mentioned body and controlled by said first mentioned means.

11. The combination with a movable body, 100 of means carried thereby and responsive to radiant energy for controlling the direction of movement of said body, a body movable independently of said first mentioned body, and steering means carried by said second 105 mentioned body and controlled by said first mentioned means for controlling the direction of movement of said second mentioned body.

12. The combination with a movable body, 110 of means carried thereby and responsive to radiant energy for controlling the direction of movement of said body, a body movable independently of said first mentioned body, and steering means including a rudder carried by said second mentioned body and controlled by said first mentioned means for controlling the direction of movement of said second mentioned body.

13. The combination with a movable body, 120 of means carried thereby and responsive to electroradiant energy for controlling the direction of movement of said body, a body movable independently of said first mentioned body and means carried by said second mentioned body and controlled by said first mentioned means for controlling the direction of movement thereof.

14. The combination with a movable body, of means carried thereby and respon- 130

- 5 sive to electroradiant energy, for controlling the direction of movement of said body, a body movable independently of said first mentioned body, and functioning means carried by said second mentioned body and controlled by said first mentioned means.
15. The combination with a movable body, of means carried thereby and responsive to electroradiant energy for controlling the direction of movement of said body, a body movable independently of said first mentioned body, and steering means carried by said second mentioned body and controlled by said first mentioned means for controlling the direction of movement of said second mentioned body.
- 20 16. The combination with a movable body, of means carried thereby and responsive to electroradiant energy, for controlling the direction of movement of said body a body movable independently of said first mentioned body, and steering means including a rudder carried by said second mentioned body and controlled by said first mentioned means for controlling the direction of movement of said second mentioned body.
- 25 17. The combination with a station for the transmission of radiant energy of a plurality of bodies normally freely movable separately and independently of said station, receiving means upon one of said bodies responsive to radiant energy transmitted from said station, and steering means upon another of said bodies and arranged to be controlled by said receiving means.
18. The combination with two separately movable bodies, of functioning means carried by one of said bodies, a solid electrical conductor operatively connecting said functioning means with the other of said bodies, and means responsive to radiant energy on said last mentioned body and acting through said conductor to control said functioning means.
19. In a system for multiple control for vessels, a primary vessel controlled by radiant energy, a secondary vessel controlled through an electric cable by said primary vessel, and automatic means for operating said secondary vessel from said primary vessel.
20. A system of multiple control for vessels, a primary vessel controlled by radiant energy, and a secondary vessel controlled through an electric cable from said primary vessel.
21. The combination with a station for the transmission of radiant energy, of a primary marine vessel, receiving means carried by said vessel and arranged to respond to radiant energy from said station to control the direction of movement of said vessel, an auxiliary vessel movable independently of said station and of said primary vessel, means carried by said auxiliary vessel and arranged to be controlled by said receiving means for controlling the direction of movement of said auxiliary vessel.
22. The combination with a station for the transmission of radiant energy, of a primary marine vessel, receiving means carried by said vessel and arranged to respond to radiant energy from said station to control the direction of movement of said vessel, an auxiliary vessel movable independently of said station and of said primary vessel, and means carried by said auxiliary vessel and arranged to be controlled by said receiving means to cause said auxiliary vessel to be moved at all times in a direction substantially parallel to the movement of said primary vessel.
23. The combination with two separately movable bodies, of steering means carried by each of said bodies, and receiving means responsive to radiant energy carried by one of said bodies and operative to control said steering means on each of said bodies.
24. The combination with two separately movable bodies, of steering means carried by each of said bodies, and receiving means responsive to radiant energy carried by one of said bodies and operative to simultaneous control said steering means on each of said bodies.
25. The combination with a station for the transmission of radiant energy, of a primary movable body, receiving means carried by said body and responsive to radiant energy transmitted from said station to control the direction of movement of said body, an auxiliary body movable with respect to said first-mentioned body, receiving means on said auxiliary body and arranged to control the direction of movement of said auxiliary body, and transmission means on said primary movable body and arranged to control said receiving means upon said auxiliary body and to be controlled as the result of the operation of said transmission station.

This specification signed and witnessed this 1st day of April, A. D. 1913.
